CLOSURE DEVICE FOR COLLAPSIBLE TUBES
AND THE LIKE

Jack Pari, New York, N. Y.

Application September 28, 1938, Serial No. 232,223

1 Claim. (Cl. 221—60)

The present invention relates to new and useful improvements in closures for collapsible tubes and has for its primary object to provide, in a manner as hereinafter set forth, a device of this 5 character embodying a novel construction, combination and arrangement of parts through the medium of which the contents of the tube or container may be readily discharged.

Other objects of the invention are to provide 10 a collapsible container closure of the aforementioned character which will be comparatively simple in construction, strong, durable, highly efficient and reliable in use, compact, light in weight, and which may be manufactured at low 15 cost.

All of the foregoing and still further objects and advantages of the invention will become apparent from a study of the following specification, taken in connection with the accompanying 20 drawing wherein like characters of reference designate corresponding parts throughout the several views, and wherein:

Figure 1 is a fragmentary vertical transverse sectional view of a container embodying my invention.

Figure 2 is a transverse sectional view taken substantially on the line 2—2 of Fig. 1.

Figure 3 is a vertical sectional view with the discharge opening disclosed.

Figure 4 is a side elevational view.

Referring now to the drawing in detail, it will be seen that the reference numeral 5 designates generally a collapsible container, constructed of metal or other suitable material, provided with a discharge tube 6. A shoulder 7 is provided at the junction of the tube 6 and container 5 upon which rests a suitable gasket 8. The discharge tube 6 has an opening 9 in the sidewall thereof and has screw threads 10 extending from the base thereof which terminate in spaced relation 40 to the top end portion of the same, while the top end portion thereof is flared outwardly as at 11.

A threaded cap 12 is threaded onto the discharge tube 6 in order to close the opening 9 when desired. The cap has integral therewith and 45 extending downwardly from the bottom side of the top thereof a projection 13 which is spaced from the inner wall of the cap to form an annu-

lar channel 14 into which the flared end portion 11 of the discharge tube 6 is engaged. The annular channel 14 is of a greater diameter than the threaded opening of the cap 12 thus forming a shoulder 15 which engages the flared end portion of the discharge tube 6 and prevents the cap 12 from separating from the same. The projection 13 is slidably engaged in the tube 6 and acts to close and prevent leakage from the container when the cap is screwed down on the thread 10 while the gasket 8 is compressed by the bottom end portion of the cap 12 to further seal the container. The projection 13 is tapered at its upper end portion as at 16 to provide means for flaring the end portion 11 on the discharge tube 15 6 when the cap 12 is fed down on the threaded tube 6.

The operation of the device is thought to be manifest but may be briefly described as follows:

When it is desired to dispense the contents of the tube the cap 12 is turned or unscrewed to disclose the opening 9 partially or all the way as desired, and then the contents are dispensed by compressing the container in the usual manner.

Although I have shown and described herein a preferred embodiment of my invention, it is to be definitely understood that I do not desire to limit the application of the invention thereto, and any change or changes may be made in the materials and in the construction and arrangement of parts within the spirit of the invention as claimed.

What is claimed is:

In a device of the character described, a closure for collapsible containers comprising a threaded smooth bored discharge nozzle having a longitudinal slot opening therein, a flanged end portion on said nozzle, a threaded cap engageable on said threaded nozzle, a plunger integral with and housed within said cap and terminating at its bottom end portion in a common plane with the bottom end of said cap for regulating the discharge flow from said longitudinal slot opening, when said cap is turned on said threaded nozzle, and a shoulder within said cap engageable with said flange to prevent the removal of said cap from said nozzle.

JACK PARI.
